CONTAINER AND METHOD OF FORMING
SAMEAllen B. Wilson, Evanston, Ill., assignor to Acme
Steel Company, Chicago, Ill., a corporation of
Illinois

Application August 27, 1937, Serial No. 161,176

3 Claims. (Cl. 93—39.1)

This invention relates to improvements in containers and its purpose is to provide a new method of forming a container comprising novel means for uniting an annular non-metallic wall and a bottom wall by means of a metallic rim. Containers of this general type are now in quite common use for shipping ice cream and various other commodities and it is important to provide a container formed largely of non-metallic members which may be readily assembled by the user without the use of rivets or other fastening means. The principal object of the present invention is to provide a new form of container comprising an annular metallic rim adapted to surround one end of the annular non-metallic wall of the container with parts thereof supporting a bottom wall and with other parts thereof adapted to move automatically into interlocking engagement with the annular wall when the rim reaches its normal position on that wall. Another object of the invention is to provide a new method of forming a container according to which an annular collapsible non-metallic wall is first expanded by the insertion of a circular end wall adapted to fit the inner diameter thereof, after which an annular metallic rim is driven over the end of the annular wall on the outside of the end wall to cause parts of the rim to bite into the material of the annular wall and other parts thereof to move to a position wherein they support the bottom wall. Another object of the invention is to provide a container having an annular non-metallic wall and a bottom wall in combination with an annular metallic rim provided with an inwardly extending transversely corrugated flange adapted to engage and support the bottom wall and having inwardly inclined resilient projections adapted to move outwardly to permit the application of the rim to the annular wall and adapted to bite into said annular wall when the rim is in place. Other objects of the invention relate to various features of construction and arrangement and to details of the method which will appear more fully hereinafter.

The nature of the invention will be understood from the following specification taken with the accompanying drawing, in which one embodiment is illustrated. In the drawing,

Figure 1 shows a perspective view of a container embodying the features of the present invention;

Fig. 2 shows an enlarged sectional view taken on the line 2—2 of Fig. 1;

Fig. 3 shows a perspective view of a metal

strip from which the rim illustrated in Fig. 1 is formed;

Fig. 4 shows a perspective view of the metal strip after it has been operated on to form the transversely corrugated flange which supports the bottom wall; and

Fig. 5 shows a side elevation of the container with the metallic rim separated from the annular wall and with parts of the container walls and rim broken away, this view illustrating the method of applying the rim to the annular wall after this wall has been expanded by the insertion of the bottom wall.

As illustrated in the drawing, the improved container comprises an annular non-metallic wall 10, formed of fiberboard or the like which is constructed by uniting the overlapping edges of a sheet of suitable material having such characteristics that the wall may be collapsed into the form of a double folded sheet for purposes of shipment in a bundle with a number of similar collapsed walls. The wall 10 is adapted to be closely fitted by a circular bottom wall 11 which may be inserted within the wall 10 to expand it, as shown in Fig. 5. The bottom wall 11 is supported in its normal position, shown in Fig. 2, by means of an annular metallic rim 12 having a body portion 12^a which closely fits the outer surface of the lower end of the wall 10 and having an upwardly and inwardly inclined transversely corrugated flange 12^b which projects beyond the wall 10 and supports the wall 11. The body portion 12^a of the rim is provided with a plurality of downwardly and inwardly inclined pointed projections 12^c, punched out of the body of the metal, which are resilient and which penetrate the material of the wall 10 when the rim is in place, as shown in Fig. 2, to prevent the withdrawal of the rim.

The rim 12 is preferably formed from a strip of sheet metal having the form shown in Fig. 3, this strip being cut away at one end as shown at 12^d to provide a tongue of lesser width than the remainder of the strip. Having provided a strip with this cutaway portion, the lower edge thereof is then bent transversely and is transversely corrugated as shown in Fig. 4 to form the flange 12^b. While the strip is in its flat condition, and either before or after forming the flange 12^b, the body portion of the strip is punched at intervals to form the inclined pointed projections 12^c which extend in the same general direction as the flange 12^b, that is, toward the inside of the resulting rim. When these parts have been formed, the strip is bent into

circular form with the flange 12^b and the projections 12^c directed inwardly, until the tongue 12^a overlaps the body of the strip at the other end thereof. The overlapping parts are then secured together by spot welds 13 or other fastening means to form the completed rim.

According to the preferred process of assembling the parts of the container, the wall 10 is first expanded by inserting therein the bottom wall 11 until this bottom wall is near the lower end of the annular wall, as shown in Fig. 5, and the rim 12 is then driven onto the lower end of the wall 10, until the flange 12^b occupies the position shown in Fig. 2 with respect to the lower end of the wall 10. During this process of driving on the rim, the projections 12^c will bend outwardly to allow the movement of the rim, but when the rim reaches its final position they tend to move inwardly, due to their own resilience, until they bite into the material of the wall 10 to prevent the withdrawal of the rim. If the bottom wall 11 is not then in position resting on the flange 12^b it may be pushed downwardly to a further extent until it is supported by this flange of the rim.

Although one form of the invention has been shown and described by way of illustration in connection with the explanation of one method of forming the container, it will be understood that the invention may be constructed in various embodiments and may be formed in various ways coming within the scope of the appended claims.

I claim:

1. The method of forming a container which comprises the operations of forming an annular collapsible non-metallic wall and an end wall

adapted to fit within said annular wall, expanding said annular wall by inserting said end wall therein, and then driving onto the end of said annular wall a complete annular metallic rim having resilient projections adapted to be deflected outwardly during the driving operation.

2. The method of forming a container which comprises the operations of forming an annular collapsible non-metallic wall and an end wall adapted to fit within said annular wall, expanding said annular wall by inserting said end wall therein, and then driving onto one end of said annular wall a complete annular metallic rim having an inwardly extending flange adapted to support said end wall and having inclined resilient projections adapted to be deflected outwardly during the driving operation and to penetrate said annular wall after said rim is in place.

3. The method of forming a container which comprises the operations of forming an annular collapsible non-metallic wall and an end wall adapted to fit within said annular wall, expanding said annular wall by inserting said end wall therein, and then driving onto one end of said annular wall a complete annular metallic rim of a size adapted to fit over said annular wall and provided with an inwardly extending flange adapted to support said end wall and also with resilient pointed projections inclined toward the adjacent end of said annular wall and adapted to be deflected outwardly during the driving operation and to penetrate said annular wall due to their own resiliency after said rim is in place thereon.

ALLEN B. WILSON.
